(57) CLAIM

The ornamental design for a wood pellet cart, as shown and described.

DESCRIPTION

FIG. 1 is a front perspective view of a wood pellet cart shown with the lid closed;

FIG. 2 is a front perspective view shown with the lid open thereof;

FIG. 3 is a front elevational view thereof;

FIG. 4 is a rear elevational view thereof;

FIG. 5 is a left elevational side view thereof;

FIG. 6 is a right elevational side view thereof;

FIG. 7 is a top plan view thereof; and,

FIG. 8 is a bottom plan view thereof.

The broken line in the figures is included for the purpose of illustrating environment and forms no part of the claimed design.
